design for an ornamented Franklin Stove, and I do hereby declare that the following is a full, clear and exact description of the same reference being had to the accompanying drawings making part of this specification, in which Fig. 1 represents a perspective view of a stove after my design — Fig. 2 represents the front, and Fig. 3, the side plate, upon a larger scale, to shew the detail of ornament.

The design is in the style of Louis XIV, and although not easily describable in words, is fully represented in the drawings — In Fig. 1, 2 is the side plate, (Fig. 3) — all the ornaments are upon a lac'd ground —

What I claim as my invention and desire to secure by Letters Patent, is the combination and arrangement of ornamental figures herein shewn and described forming a design for an ornamented Franklin Stove.
